CHANGE-OVER ASSEMBLY

Frank Pedatella, New Kensington, Pa., assignor
to Wilbert C. Black, New Kensington, Pa.

Application September 12, 1935, Serial No. 40,260

6 Claims. (Cl. 88—16.2)

This invention relates to an automatic change-over for changing over from one reel of film to another in motion picture projection, and relates to the combination of an automatic changeover 5 of that nature with safety control means mechanically and electrically cooperative with changeover elements proper, to carry forward the operation of normal changeover, and to guard against destructive effects which may result from 10 abnormal conditions of the film.

The object of my invention is to provide a 15 changeover assembly, associated with safety control features, which is of improved simplicity, both electrically and mechanically, which is positive and wholly automatic in its operation, and which is relatively inexpensive to manufacture and install.

In the accompanying drawings Fig. I is a view, 20 partly in side elevation and partly in vertical section, of a projection assembly comprising, primarily, a lamp, or light, house and shutter therefor; a projection lens and mounting, with shutter therefor; a sound head; and motor driven means for passing film between the light source and the 25 projection lens.

Fig. II is a detail view, in side elevation, showing an automatic safety switch, or "trap," operated by a loop of the film, and arranged to bring into play the safety control elements of the assembly upon abnormal condition of the film loop.

Fig. III is an end elevation of the switch, or trap, shown in Fig. II.

Fig. IV is a front elevation of a film-operated trigger mechanism, arranged to initiate normal 35 changeover activity, and of a second film-operated, automatic safety switch, or "trap," as mounted in physical association with trigger mechanism.

Fig. V is a vertical, sectional view, through the 40 trigger mechanism and "trap" shown in Fig. IV, taken on the section line V—V of Fig. IV.

Fig. VI is a vertical, sectional view of a third 45 automatic, film-operated safety switch, or "trap," arranged also to effect safety control upon abnormal condition of the film.

Fig. VII is a horizontal, sectional view, through this third automatic safety switch, or trap, taken on the section line VII—VII of Fig. VI.

Fig. VIII is a front elevation of the shutter 50 mounted in front of the lamp-house of the projection assembly, and of safety control contact elements associated with, and operated in accordance with movement of, the lamp-house shutter.

Fig. IX is a vertical, sectional view, taken on 55 the line IX—IX of Fig. VIII.

Fig. X is a front elevation of the shutter for the projection lens of the assembly, showing operating means for the shutter, and circuit control contacts associated with the shutter control mechanism, and arranged to be operated thereby. 5

Fig. XI is a wiring diagram showing the wiring and contacts of two projection assemblies, together with the motor and sound-energizing circuits for the assemblies, and the conductors and contacts for effecting normal changeover between motors and sound sources, together with circuits and contacts for controlling the shutters of the two projection assemblies, both in the normal changeover sequence, and upon the existence of various abnormal conditions which may require the operation of safety control. 10 15

Referring to Fig. I of the drawings, reference numeral 1 designates a lamp-house having therein a light source for producing the image-projecting light-beam. Mounted before opening 20 1a of the lamp-house is a funnel-shaped light-shield 2, before which is mounted shutter mechanism designated generally by reference numeral 3, and actuated by mechanism housed in a casing 4, which serves as a mounting pedestal for the 25 shutter. In horizontal alignment with light shield 2 and shutter 3 is an assembly, of usual sort, carrying a projecting lens 5. A second shutter 6 is movably mounted before the lens 5 upon a casing 7, which serves as a pedestal for 30 the shutter mechanism, and which contains operating means for moving the shutter.

The film, designated by reference letter A, is taken from a supply reel 8 by a winding reel 9 actuated by motor 10. The above elements, 35 broadly considered, are well known in the art, and are found in one form or the other in standard projection assemblies. In accordance also with known practice in providing safety control for the assembly, I provide a plurality of film-operated, automatic safety switches, or traps, 40 arranged to control the operation of safety mechanism for preventing fire hazards due to abnormal conditions of the film; and, as is also usual, I provide means acted upon by the film, 45 automatically to effect a changeover from one projection assembly to another at a predetermined point in the unreeling of the film, such point being adjacent the film terminal. In my assembly, however, the several film-operated 50 safety switches, or traps, are of novel and particularly efficient structure, and a film-operated means for initiating normal changeover is also of novel and particularly efficient structure.

Referring still to Fig. I of the drawings, refer- 55

ence numeral 11 designates generally a safety switch, or trap, positioned adjacent the supply reel 8, and effective upon abnormal condition of a loop A' of the film. The physical assembly 5 of trigger mechanism for initiating normal changeover, and a safety switch, or trap, effective upon abnormal condition of the film, are shown diagrammatically, and are designated generally by reference numerals 12 and 12a. 10 A third safety switch, or trap, 13 is shown diagrammatically adjacent the winding reel 9 of the projection assembly.

It may be well generally to relate the operations of normal changeover, and the operation of safety 15 control, as automatically performed by my apparatus, before describing in detail the energizing and controlling circuits involved, and the specific mechanism associated with the circuits. 20

Let us assume that operating conditions in both 25 projectors are normal, and that the film A on the supply reel of the active projector approaches exhaustion. At a substantial interval before complete exhaustion of the film, trigger mechanism 12 acts, under the influence of the film, to complete a circuit to the motor of the inactive 30 projection assembly. This lead gives time for the motor of the inactive assembly to gather speed before that assembly is called upon to continue the projection and sound from the film mounted 35 in it. The starting of the motor of the hitherto inactive projection assembly is effected by elements of the safety control mechanism associated with that assembly. Initially, it is desired to emphasize the fact that, in my automatic 40 changeover and safety control, the safety control performs a dual function, taking part in the sequential progress of normal changeover, as well as performing its safety function. The effect produced by the changeover mechanism of the 45 inactive changeover assembly is to open the lamp-house shutter 3 of that assembly, as well as completing a circuit to the motor of the inactive assembly.

At a point closer to the film terminal of the 50 active projection assembly, the film acts upon trigger mechanism 12, to initiate such action that a movable part of the mechanism for controlling lens shutter 6 of the active assembly is shifted. This shifting mechanically effects movement of the shutter 6 from its opened position 55 to its closed position before the lens 5; and, simultaneously, movement of this part, which closes the shutter before the projecting means of the previously active assembly, acts to break a circuit from that assembly to the sound head.

At the same time, a similar movable part in the means for operating the shutter 6 of the hitherto inactive projection assembly is moved, opening the lens shutter associated with that assembly, and completing a circuit, associated with the film of that assembly to the sound head. The final stage of normal changeover is effected 60 by the film trap 12a, this trap acting to complete a controlling circuit to the safety control means 65 of the assembly, which has been operative, to produce action closing the lamp-house shutter 3 of that assembly, and to cut the energizing circuit to the motor 10 of the assembly. The changeover from one projection assembly to the 70 other is then complete.

Initially, I shall refer to the film-operated switch mechanism, shown in detail in Figs. IV and V of the drawings, it being understood that each of the pairs of projection assemblies between which changeover is made is equipped with

identical switch mechanism. This switch mechanism, which has been designated generally by reference numeral 12, comprises two pivoted arms 15 and 15a, which are arranged, respectively, to close the pairs of spring contacts 16 and 16a by means of a cam terminal 17, which is formed at the proximal ends of each of the arms 15 and 15a adjacent the pivot point 18 of the arm. At its distal end, each of the pivoted arms 15 and 15a is provided with fingers 19 and 19a, which are forced outwardly by means of a coil spring 20 mounted in the arm. The fingers 19 and 19a of the two arms 15 and 15a project, respectively, through slots 21 and 21a formed in the curved forward face 23 of housing 22, in which the arms 15 are mounted.

The film A passes, in contact with the upper region of the curved forward face 23 of housing 22, through the slots in which the fingers 19 and 19a project, and is held against this upper region of the housing face by a bar 24, which is carried by an arm 25, pivoted in the housing, and acted upon by past-center spring 26. In operative position, with the film A inserted, the effect of spring 26 is to hold the bar 24 to the film. 25 When the arm 25 is thrown upwardly, to a past-center position, as shown in broken lines in Fig. V, the past-center spring so holds the arm until it has manually been returned to its film-grasping position. 30

During operation of a projection assembly, with the parts in the position shown in Fig. V, the fingers 19 and 19a lie at the upper terminals of the slots 23 and 23a in which they move, and bear against the presented face of the film A. 35 It will be noted that the spacing between the arms 15 and 15a, which carry the fingers 19 and 19a, is relatively slight, so that the fingers are spaced apart a distance substantially less than the width of the film. 40

On the film, adjacent its supply reel terminal, are two apertures, spaced from each other longitudinally of the film, and each in line with one of the fingers 19 or 19a. These film openings lie well within the sprocket openings in the film by which the film is transferred from the supply reel 8 to the winding reel 9. As the film A approaches exhaustion, the more advanced one of the openings therein comes into alignment with the finger 19, which is constantly pressed outwardly against the film by its associated spring 20. The finger 19 being engaged by this film opening, the arm 15 is rotated about its pivot, during a short distance of film travel, and during this travel is so rotated about its pivot 18 that the proximal cam 55 surface 17 on the arm acts upon spring contacts 16 to close them, and to complete a circuit, the effect of which will be hereinafter described.

Adjacent the lower end of curved face 23 is a roller 27, forming an element of trap 12a, which is carried by a yoke 28, having at its inner terminal a second roller 29. Roller 29 lies between a fixed plate 30, and a resilient plate 31a, forming an element of spring contact pair 31. Omitting for the present the contact controlling function of the structure, the spring plate 31 forces roller 27 outwardly against the film, the rearward, or inward, limit of movement of the roller being defined by a nut 32, threaded to one arm of the yoke 28, and arranged to bear against an apertured face 33 of the housing 22. This roller 27 acts, therefore, to hold film A outwardly a predetermined distance from the lower region of the curved housing face 23. 70

When finger 15 has travelled a sufficient dis- 75

tance, it is freed of the opening in the film A, since the film is, by the roller 27, held away from the curved face 23 of the housing in which the finger rides. The action is thus momentarily to make 5 and rapidly to break electrical connection through spring contacts 16. When the second finger 19a is engaged by the second film aperture, it similarly is swung downwardly by the film, momentarily making its associated contacts 16a, and 10 permitting these contacts to open as the arm swings through the arc predetermined by the position of the film with respect to the face 23 of the housing.

Referring to the wiring diagram of Fig. XI, it 15 will be seen that the closing of contacts 16 completes a circuit *a* leading from the line conductor *b* to a coil 34 in the safety control mechanism of the inactive assembly. The effect of energizing coil 34 is to draw into it a plunger, which makes 20 contacts 35, completing a circuit *c* from conductor *b'* of the line circuit to the motor 10 associated with the inactive assembly. This starts the motor of the inactive assembly, giving it the lead above referred to. Simultaneously, energization 25 of coil 34 closes contacts 35a in the safety control of the inactive assembly in preparation for the completion of a circuit *d* to the sound mechanism of the inactive assembly.

Reference will here be made to the specific 30 structure of the safety control mechanism associated in each projection assembly. Referring to Figs. VIII and IX of the drawings, I have shown lamp-house shutter 3, which is mounted adjacent or in sliding contact with a plate 36, having 35 therein an aperture 37 in line with light-cone 2 (Fig. I) in front of the lamp-house. Coil 34, above referred to, is one of a pair of coils 34 and 34a arranged to act oppositely upon a plunger 38, which has a slot and pin connection 39, with an extended arm portion 3a of the shutter 3. Movement of core 38 to the left of Fig. VIII, into the position shown, under the energization of coil 34, shifts cam 40, on a cross-shaft 41, and fixed to shutter extension 3a, into position 45 permitting spring contacts 35 to close. On the other face of plate 36, and at the opposite end of shaft 41, is a second cam 40a. This cam controls the spring contacts 35a, and, similarly, in the position illustrated in Fig. VIII of the drawings, is so shifted as to permit these contacts 50 to close in preparation, as has been explained, for the completion of the sound circuit of the assembly.

The mechanical effect of moving core 38 to the 55 left of Fig. VIII is to shift shutter 3 to the right, exposing opening 37 through plate 36. This removes the obstruction to the emission of light from the lamp-house of the inactive assembly.

It will be noted in Fig. VIII that the plunger 38 60 is of relatively great length, so that its projection in one direction or the other is substantially beyond coil 34 or coil 34a. As shown, this plunger has acted mechanically to separate spring contacts 42, which control the connection of the coil 65 to the energizing circuit *a*, thus interrupting that circuit. Simultaneously, withdrawal of the plunger from physical contact with a pair of spring contacts 43 has permitted these contacts to close, thereby preparing a circuit *d*, the function 70 of which will be hereinafter described in connection with the feature of safety control.

This completes the effect directly attributable 75 to the film-actuated swinging of arm 15, resulting in making its associated contacts 16. It may be observed that the action described is self-clear-

ing, since the spring contacts 16 open when finger 19 rides out of its associated film aperture releasing the arm 15, and since coil 34, which opens the lamp-house shutter, which starts the motor of the inactive assembly, and which prepares a circuit to sound, is self-deenergizing because of the action of plunger 38. 5

The second finger 16a, in swinging downwardly upon engagement with the opening in the film, by similarly completing momentarily its associated 10 spring contacts 16a, completes a circuit *e* to the coil 44 associated with the projection shutter mechanism of the active assembly, and with a coil 44a associated with the projection shutter of the inactive assembly. The circuit *e*, arranged 15 to energize oppositely acting coils in the shutter-operating mechanism of the two assemblies, takes current from the line conductor 6.

Referring to the shutter mechanism, as shown 20 in Fig. X of the drawings, this shutter mechanism also comprises an elongate core 45, which is moved in opposite directions by coils 44 and 44a. Projection shutter 6 acts against a plate 46, which has therein an aperture aligned with lens 5, all as has been previously noted. On shutter 6 25 is an extended arm portion 6a, which has a slot and pin connection 47 with the plunger 45. A cam 48, physically mounted on the face of shutter arm 6a, acts in swinging movement of the shutter in one direction or the other to open 30 spring contacts 49, or to permit them to close. The shutter swings about a center provided by a shaft, passing through the cam 48 and plate 46, similar to the shaft 41 described in connection with the safety control mechanism. 35

Fig. X of the drawings shows the effect of the closing of contacts 16a upon the projection shutter mechanism of the still active assembly. In this position of the parts, the shutter has been closed by swinging the shutter proper to the left, 40 with the extended portion 6a of the shutter carried to the right by its engagement with core 45. Simultaneously, plunger 45 has acted mechanically to separate spring contacts 50 controlling a circuit *d* to the sound mechanism of that assembly. Contacts 49 being open interrupt the circuit *a* forming the other side of circuit *e*, thus deenergizing the coil 44 in the projection assembly which is about to discontinue activity, and also energizing the coil 44a in the projection assembly which is to assume activity. 45 50

Taking the operating mechanism for the lens shutter in the other projection assembly, the action is the reverse of that described, and involves a movement of the plunger 45 from the position 55 shown in Fig. X to the left. This action uncovers the aperture, previously shielded by shutter 6, and permits spring contacts 50 to close, thus completing the circuit *d* to the sound mechanism of that assembly, and permitting spring 60 contacts 49 also to close. The closing of contacts 49 merely prepares a circuit to the open contacts 16 and 16a associated with the switch mechanism of this second assembly.

Referring specifically to Figs. IV and V of the 65 drawings, the roller 27, forced outwardly against the film A, by the spring plate 31a of spring contact pair 31, has been hereinabove mentioned as an element holding the film outwardly from the lower region of curved face 23 of the switch 70 housing. It will be noted that roller 29, carried by yoke 28 inwardly of the switch housing, is resiliently pressed by spring plate 31a against the fixed plate 30. In this position, which is shown in Fig. V, roller 29 thus acts to hold spring plate 75

31a against the floor of the housing 22, thereby maintaining the spring contacts separated.

It will be noted that the forward extremity of spring plate 31a is inclined downwardly. When 5 the film A is wholly wound from its supply reel 8, the action of spring plate 31a forces the assembly of yoke 28 and rollers 27 and 29 outwardly into the dotted line position shown in Fig. V. In this action, roller 29, moving down the incline 10 of spring plate 31a, ceases to hold the contacts separated, because of the increased interval between the upper face of the spring plate and the under face of the fixed plate 30.

Spring contacts 31, in closing, complete a circuit 15 to the coil 34a of the motor which has been active to propel the running film. Referring to Fig. VIII of the drawings, this coil 34a shifts plunger 38 to the right, as shown in Fig. VIII, so that cam 40 separates spring contacts 35, thus 20 breaking the circuit to the running motor 10 associated with this projection assembly, and also separating, at the safety control, the spring contacts 35a which serve, when closed, to prepare a circuit to the sound mechanism of that 25 projection assembly.

Simultaneously, shutter 3 is moved into position to close the opening 37 in plate 36, thereby screening the lamp-house of the projection assembly which is thus going out of action. Also 30 the mechanical action of core 38 serves to open spring contacts 43, and to permit spring contacts 42 to close, thus placing this safety control in condition to be energized when the projection assembly, which has now become active, in turn, 35 prepares to go out of action. This completes the changeover cycle, activity having been fully transferred from one projection assembly to the other.

Referring to circuit f, by which the final steps 40 in eliminating a projection assembly from activity is effected during changeover, but referring to the right-hand side of the wiring diagram, representing a projection assembly in which activity has been set up, it should be noted that this circuit f, associated with contacts 42, which are 45 to be considered closed, is primarily involved in the safety control function of the mechanism. There are effective in it, to produce safety control action, the three automatic switches, or traps, 11, 12a and 13. As so designated, it is to be 50 understood that reference numeral 12a, relates generally to the switch mechanism comprising the film-contacting roller 27 arranged to bear against the inner side of the film, and mounted in the switch housing 22 in association with switch mechanism 12.

Safety switch, or trap, 11, shown in detail in Figs. II and III of the drawings, is operated by the loop in film A, which is formed between its supply reel 8 and the point at which it is subjected 60 to the projecting light-beam, which loop serves to prevent whipping of the film as it passes before the light-beam. This switch mechanism comprises a bell crank lever 51, pivotally mounted at 52, on a supporting structure 53. The longer and outwardly projecting arm of the bell crank carries a roller 54, while the shorter and inwardly projecting arm of the bell crank has a terminal 55 of insulating material, which is arranged to act upon a pair of spring contacts 56. Pivotedly mounted at 57, on the supporting structure 65 53, is an arm 58, which has extending forwardly and upwardly therefrom a hook portion 58a, and which has extending rearwardly and downwardly therefrom a leg 58b, which contacts 70

bell crank lever 51 adjacent its pivotal mounting 52.

The loop of film A is passed between roller 54 and hook 58a, and in normal condition the loop comes into contact with neither of them. If, 5 however, due to abnormal lessening in tension, the loop of film A should so rise as forcefully to contact hook 58a, arm 58 is rotated about its pivot 57, and the leg 58b rotates bell crank 51 causing its terminal 55 to make the contacts 56. 10 If, on the contrary, due to abnormally high tension on the film A, the film is forcefully brought into contact with roller 54, bell crank 51 is swung about its pivot in the same direction of rotation as that previously described, in such event also 15 making contacts 56.

Contacts 56, being made by either noted abnormal condition of the film loop, solenoid coil 34a is energized, shifting the shutter 3 from its position exposing the opening 37 to its position 20 closing the opening 37, breaking the circuit to the running motor, and also breaking the circuit to sound. In all respects the action of safety control is identical with the action described in connection with the ultimate stage of deactivating a projection assembly in changeover, save 25 that the effect of separating sound control contacts 35a, is to interrupt an active circuit to sound, rather than merely to interrupt a preparatory circuit to sound.

The action of the safety switch, or trap, 12a, which comprises film-contacting roller 27, occurs as a safety action if the film be broken at a point between that trap 12a and the supply reel 8. Upon breakage of the film, the function 35 of the safety switch, or trap, 12a, is identical with that described in connection with the movement of the film terminal past the roller 27. This safety switch, or trap, 12a, also acts, however, to effect safety control under conditions which 40 do not involve actual film breakage. Thus, if there is disengagement from the film of the sprocket forming part of winding reel 9, or if such winding reel should for any cause fail to rotate, a loose loop is formed in the film intermediate the 45 reels 8 and 9. This relief of tension against roller 27 permits the mechanism of safety switch 12a to act similarly to breakage of the film in effecting safety control. This quality of the safety switch, or trap, 12a is of importance, in that it serves 50 frequently to anticipate, and prevent, film breakage.

The third safety switch, or trap, designated generally by reference numeral 13, is disposed relatively close to the winding reel 9. This safety 55 switch, or trap, 13, effects safety control upon abnormal film conditions existing between safety switch 12 and winding reel 9. Upon film breakage between the safety switches 12 and 13 it acts to effect safety control. Also, if winding reel 9 60 should fail to operate, and the effect should be to form a loose loop adjacent the winding reel, rather than in the regions of the film lying closer to supply reel 8, this safety switch acts to effect safety control in manner identical with that in 65 which safety control is effected by either of safety switches 11 or 12a.

Referring to Figs. VI and VII of the drawings, safety switch assembly 13 comprises a housing 59, 70 which contains a spring contact pair 60, the spring contacts of the pair being convergently formed in their regions 60a adjacent the contact mounting 61. Lying between the spring contacts of the pair is a roller 62, which is mounted on a 75

yoke 63, carrying at its outer terminal a second roller 64.

In normal condition of the film A, the pressure of the film against outer roller 64 maintains roller 62 in inwardly forced position, so to act upon the converging region 60a of the spring contact elements as to maintain these contact elements separated. When, however, breakage, or lack of tension, of film A relieves the inwardly directed pressure on the yoke 63, and rollers carried by it, the resilience of the spring contacts 60 acts to force the roller assembly outwardly, thus relieving the spring contacts of the separating effect of roller 62, and permitting the spring contacts to close.

The safety control elements, above described, prevent fire hazard, and avoid destruction of a film, due to the existence of abnormal conditions, accompanied by continued activity of the motor actuating the winding reel 9. They also, by breaking the connection to the sound mechanism, prevent the emission of unpleasant noises under such conditions.

In my changeover and safety control assembly I provide, however, additional means, arranged to act upon the blowing of a fuse, or some such line circuit interruption as would cause the motor driving winding reel 9 to cease its activity, without, however, affecting the tension on the film. Under such circumstances, movement of the film being suspended, the light-beam from the lamp-house 1, impinging uninterruptedly against a particular restricted area of the film, tends to injure the film, or even to cause it to ignite. Such additional safety means comprise a holding magnet 65, which is connected across the line conductors b and b'. Opposed to the attractive force of holding magnet 65 is a spring 66, which exerts a force tending to move a contact element 67 to interconnect contact pairs 68, 69, and 70.

If, then, the line circuit be interrupted, these contact pairs 68, 69, and 70, are interconnected, completing three circuits to an emergency light system 71. Interconnection of contacts 68 completes a conductor g; interconnection of contacts 69 completes a conductor h; and interconnection of contacts 70 completes a conductor i.

If, then, the projection assembly, to the left of the wiring diagram, be active, a circuit is completed, at contacts 68, through conductor g to the circuit f, leading to the coil 34a of the safety control mechanism associated in that projection assembly. Energization of coil 34a effects safety control in the manner previously described. If, on the contrary, the projection assembly, shown to the right in the wiring diagram, be active, the conductor h is completed at contacts 69, providing a circuit to the coil 34a of the safety control mechanism associated in that assembly, and similarly producing the typical safety control action.

If the interruption in the line circuit occurs at an interval during changeover, in which both safety control shutters are open, the interconnection of contacts 70 completes a conductor j in electrical communication with both coils of both safety control mechanisms. This connection is effective to the coils 34a in the mechanism of both the projection assemblies; the safety control contacts 43, associated with the two coils 34a, being under such condition closed, while the contacts 42, controlling connection to the coils 34 of each assembly, are open.

I wish to emphasize the fact that, both electrically and structurally, my changeover and

safety control assembly is of great simplicity, and wish particularly to emphasize the fact that the mechanical elements constituting the safety control associated with the lamp-house shutter, the control associated with the projection lens shutter, the film-operated switch mechanism which initiates changeover action, and the several types of safety switch incorporated in the assembly, are all of unusual simplicity, and structurally are so formed that they may be made at low cost. Considering my changeover and safety control assembly as mechanism comprising a number of particular elements, which are added to the projection assemblies themselves, my invention has merit in rendering financially possible, or financially attractive, to the operators of motion picture installations, the addition of automatic changeover and safety control therefor.

It should be understood that throughout the assembly parts which are in physical contact with conductive contact elements, such as the cams 11, the film-operated arms 15 and 15a, the cams 40 and 48 carried by the lamp-house shutter and the projection lens shutter, respectively, and the various rollers 29 and 62, are all formed of insulating material. Also, it should be noted that an insulating washer 80 is provided on each spring contact element with which either of the cores 38 and 45 comes into physical contact. Further, it may be noted that in my complete assembly all coils, save the coil of holding magnet 65, are self-deenergizing, so that no measurable power consumption is involved in their operation. Holding magnet 65 may be so made that its power consumption is very slight.

I claim as my invention:

1. In a motion picture projection installation the combination of two projection assemblies each comprising a lamp-house a projector a film-propelling motor and sound mechanism, a lamp-house shutter having electromagnetic shifting means therefor associated in each projection assembly, a projector shutter having electromagnetic shifting means therefor associated in each projection assembly, a film-operable switch element in each assembly arranged to cause shifting of the lamp-house shutter of the alternate assembly, a film-operable switch element in each assembly arranged to cause shifting of its proximal projector shutter, connection arranged to cause shifting of each projector shutter upon shifting of the projector shutter associated in the alternate assembly, said shifting of the two projector shutters being opposite in sense, a film-operable switch element in each assembly arranged to cause shifting of its proximal lamp-house shutter, a switch directly associated with each lamp-house shutter and operable by shifting movement thereof controlling the proximal film-propelling motor, and a switch similarly associated with each lamp-house shutter and a switch similarly associated with each projector shutter cooperatively effective for controlling activity in the sound mechanism of the two assemblies.

2. In a motion picture projection installation the combination of a projection assembly comprising a lamp-house a lamp-house shutter sound mechanism and a film-propelling motor with electromagnetic means for shifting the lamp-house shutter between open and closed positions, switches associated with the lamp-house shutter arranged to control energization respectively of the film-propelling motor and the sound mechanism of the assembly to inhibit operation of the

same by shifting of the lamp-house shutter from open position to closed position, at least one switch element arranged to produce shifting of said lamp-house shutter from open position to closed position upon relief of film tension thereon, an additional switch element arranged to shift said lamp-house shutter from open position to closed position, with an identical alternate assembly, and identical switch elements in both assemblies arranged to be film operated each to produce shifting movement of the lamp-house shutter of the other assembly to open position.

3. In a motion picture projecting installation the combination of two projection assemblies each comprising a lamp-house a projector a film-propelling motor and sound mechanism, with switches arranged in each assembly to produce action energizing the film-propelling motor and sound mechanism of the alternate assembly, a switch element associated with electrical and mechanical means arranged upon relief of tension by complete film exhaustion in each assembly to terminate the activity of the film-propelling motor in that assembly, additional switch elements arranged similarly to act upon the same to produce a termination of activity of the film-propelling motor under abnormal film conditions, independent connections for supplying electrical current respectively to each of the film-propelling motors and the lamp-houses of the two assemblies, and an electromagnet controlled switch arranged to shift the lamp-house shutter of either assembly to closed position upon interruption of current supply to the film-propelling motor proximal thereto.

4. In a motion picture projecting installation the combination of two projection assemblies each comprising a lamp-house a projector a film-propelling motor a lamp-house shutter, with electromagnetic means for moving the lamp-house shutter into open position and into closed position, switches controlling individually the two motors of the projection assemblies mounted for operation each by movement of a lamp-house shutter, independent connections for supplying electrical current respectively to each of the film-propelling motors and the lamp-houses of the two assemblies, and an electromagnet controlled switch arranged to move either lamp-house shutter to closed position upon interruption of current supply to the film-propelling motor proximal thereto.

rent supply to the film-propelling motor proximal thereto.

5. In a motor picture projecting installation the combination of two projection assemblies each comprising a lamp-house a projector a film-propelling motor a lamp house shutter movable alternatively into open and closed position, electromagnetic means for moving the lamp-house shutter into open position and into closed position, switches controlling individually the two motors of the projection assemblies mounted for operation each by movement of a lamp-house shutter, a film-contacting switch arranged upon release of film pressure thereon to cause energization of said electromagnetic means for moving the lamp-house shutter to closed position and by shutter movement to act upon the controlling switch associated with the shutter, at least one additional film-operated switch arranged under abnormal film conditions similarly to energize said electromagnetic means, independent connections for supplying electrical current respectively to each of the film-propelling motors and the lamp-houses of the two assemblies, and an electromagnet controlled switch arranged to move either lamp-house shutter to closed position upon interruption of current supply to the film-propelling motor proximal thereto.

6. In a motor picture projection installation the combination of two projection assemblies each comprising a lamp house, a projector, a film-propelling motor, and sound mechanism, with a switch structure in each projection assembly arranged to control a circuit to the film-propelling motor of that projection assembly, electro-magnetic means arranged to operate the said switches of the two projection assemblies, and film-operable switches arranged to control energization of said electro-magnetic means, the said film-operated switch of each projection assembly being arranged to act upon the electro-magnetic means of the alternate projection assembly to cause energization of the film-propelling motor thereof before deenergization of the film-propelling motor in its own projection assembly, said film-operated switches comprising each two electrical make-and-break devices severally operated by swinging fingers cooperating with the film.
